UNITED STATES PATENT OFFICE.

SIGMUND STERNAU, OF NEW YORK, N. Y.

DESIGN FOR A KETTLE.

SPECIFICATION forming part of Design No. 23,986, dated February 5, 1895.

Application filed October 6, 1894. Serial No. 525,174. Term of patent 3½ years.

To all whom it may concern:

Be it known that I, SIGMUND STERNAU, a citizen of the United States, residing in New York, county of New York, and State of New York, have invented and produced a new and original Design for Kettles, of which the following is a specification, reference being had to the accompanying drawing, which shows the kettle in perspective.

10 The leading or characteristic feature of my design is the kettle body, having the outline shown, that is, the lower portion of the body made of comparatively straight sides, the upper portion of the body comparatively flat, and the base small and shallow in comparison to the size and depth of the body.

A is the lower portion of the body of the kettle, having comparatively straight sides and B the upper portion, the outline of which is in the form of a compound curve.

20 C is the base comparatively small and shallow and D the handle extending upwardly from the body of the kettle and shaped as shown.

E is the spout, and F the top or lid.

What I claim is—

The design for a kettle as hereinabove shown and described.

SIGMUND STERNAU.

Witnesses:

GEORGE COOK,
F. S. KENNEDY.
